UNITED STATES PATENT OFFICE.

JOSEPH S. DIKEMAN, OF TORRINGTON, CONNECTICUT.

SEAT-POST BINDER.

SPECIFICATION forming part of Letters Patent No. 655,766, dated August 14, 1900.

Application filed May 19, 1899. Serial No. 717,437. (No model.)

To all whom it may concern:

Be it known that I, JOSEPH S. DIKEMAN, a resident of Torrington, in the county of Litchfield and State of Connecticut, have invented 5 certain new and useful Improvements in Seat-Post Binders; and I do hereby declare the following to be a full, clear, and exact description of the invention, such as will enable others skilled in the art to which it appertains 10 to make and use the same.

My invention relates to an improvement in seat-post binders for bicycles and the like, the object of the invention being to provide a device of the above-mentioned character 15 which will be extremely simple in construction, cheap to manufacture, easy to operate, and most effectual when in use.

With these objects in view the invention consists in certain novel features of construction and combinations and arrangements of parts, as will be more fully hereinafter described, and pointed out in the claim.

In the accompanying drawings, Figure 1 is a view in section, illustrating my improvements; and Figs. 2 and 3 are views of details.

A represents a portion of the frame of an ordinary bicycle, and B a coupling connecting the tubes of the frame together. The coupling B is provided with an internal annular shoulder 1 between its ends, on which the lower section 2 of my improved locking-tube is disposed. The lower edge of the section 2 is provided with a recess 4, in which a screw or pin 5, passing through the coupling 30 B, is disposed, so as to prevent revoluble movement of said section 2. The locking-tube comprises two sections 2 and 3, one above the other and having their meeting edges beveled or inclined. The sections 2 and 3 35 are preferably made from a tube cut diagonally, as clearly shown in Fig. 3.

The interior diameter of the coupling B is slightly greater than the exterior diameter of the sections 2 and 3 to permit of a slightly-lateral movement of said sections, as will be 45 more fully hereinafter explained.

The upper end of the coupling B is provided with internal screw-threads to mesh with external screw-threads on a nut or ring 6. The 50 nut or ring 6 is made with oppositely-disposed sockets 7 to receive a suitable tool for turning the same, or it may be made angular for the reception of a wrench or other tool.

The internal diameter of the ring 6 is approximately the same as the internal diameter of 55

the locking-tube sections and bears upon the upper end of the upper section 3.

The saddle-post 8 is passed through the nut or ring 6 and the sections of the locking-tube and the nut or ring is then screwed down. 60 As the nut or ring moves downward it will force the upper section 3 of the locking-tube to one side and the lower section 2 to the opposite side, due to the inclined bearing edges of said sections, and hence bind tightly 65 against the saddle-post and secure the same against vertical movement, while the screw 5 in the recess in the lower section 2 of the locking-tube will prevent any revoluble movement of the tube and post. 70

Various slight changes might be resorted to in the general form and arrangement of the several parts described without departing from the spirit and scope of my invention, and hence I would have it understood 75 that I do not wish to limit myself to the precise details set forth, but consider myself at liberty to make such slight changes and alterations as fairly fall within the spirit and scope of my invention. 80

Having fully described my invention, what I claim as new, and desire to secure by Letters Patent, is—

In a seat-post binder, the combination with a tubular section having an internal annular shoulder, and a seat-post entering said tubular section, of two sleeves located one upon the other and disposed loosely within the tubular section so as to embrace the seat-post, the lower sleeve resting on said annular 85 shoulder in the tubular section, the lower sleeve having a single transversely-beveled upper edge and the upper sleeve having a single transversely-beveled lower edge resting upon the beveled upper end of the lower 90 section and a nut or ring threaded into the upper end of the tubular section and bearing upon the upper sleeve so as to exert a pressure thereon and cause said sleeves to be displaced laterally in opposite directions and 95 tightly embrace the seat-post throughout the length of the two sleeves. 100

In testimony whereof I have signed this specification in the presence of two subscribing witnesses.

JOSEPH S. DIKEMAN.
